(57) **CLAIM**

The ornamental design for a bird repelling device, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top, view for a bird repelling device shown in yellow and black showing my new design;

FIG. 2 is a top, view for said bird repelling device shown in black and white thereof;

FIG. 3 is a side view thereof with the remaining side views being the same;

FIG. 4 is a view with the device formed in a triangular bar thereof;

FIG. 5 is a view with the device formed in a half circle bar thereof;

FIG. 6 is a view with the device formed in a full circle bar with a hem thereof;

FIG. 7 is a view with the device formed in a windmill thereof;

FIG. 8 is a perspective view of the device formed in a wind-sock thereof;

FIG. 9 is a perspective view of the device formed in a collection of ribbon streamers thereof; and,

FIG. 10 is a perspective view of the device formed in a half circle on an "I" beam thereof.

The broken lines and or broken image(s) in FIGS. 4, 5, 6, 7, 8, 9 and 10 depict environmental subject matter only and form no part of the claimed design.
